Primary Examiner — Antoine D Davis(74) *Attorney, Agent, or Firm* — Gerald E. Hespos;
Michael J. Porco; Matthew T. Hespos**CLAIM**The ornamental design for an electronic power meter, as
shown and described.**DESCRIPTION**FIG. 1 is a front, left perspective view of an electronic power
meter showing our new design;

FIG. 2 is a rear, left perspective view thereof;

FIG. 3 is a rear, right perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines are for the purpose of illustrating portions
of the electronic power meter and form no part of the
claimed design.**1 Claim, 9 Drawing Sheets**| (56)	References Cited
